UNITED STATES PATENT OFFICE.

FREDERICK C. BAKER, OF PORTLAND, OREGON.

DESIGN FOR AN ELECTRIC-LIGHT HANGING-LAMP FIXTURE.

47,982.

Specification for Design.

Patented Oct. 19, 1915.

Application filed February 26, 1915. Serial No. 10,874. Term of patent 7 years.

To all whom it may concern:

Be it known that I, FREDERICK C. BAKER, a citizen of the United States, residing at Portland, in the county of Multnomah and State of Oregon, have invented a new, original, and ornamental Design for an Electric-Light Hanging-Lamp Fixture, of which the following is a specification, reference being had to the accompanying drawing, forming a part thereof.

Figure 1 shows a bottom or underside view of my fixture, and Fig. 2 is a front elevation of the same.

I claim:

The ornamental design for an electric light hanging lamp fixture, substantially as shown.

F. C. BAKER.

Witnesses:

W. M. F. SCHMITT,

D. E. CRABB.
